ANTI-THUMB SUCKING DEVICE

Thomas E. Allen, 106 W. 16th St.,
Mount Pleasant, Tex. 75455

Filed Apr. 18, 1968, Ser. No. 11,513

Term of patent 14 years

U.S. Cl. D83—1
Int. Cl. D24—99

The figure is a perspective view of an anti-thumb sucking device showing my new design.

The dominant features of my design reside in the portions shown in full lines.

I claim:

The ornamental design for an anti-thumb sucking device, substantially as shown and described.
